UNITED STATES PATENT OFFICE

2,654,871

CATHODE-RAY TUBE SOCKET

Donald B. Keim, Syracuse, N. Y., assignor to
General Electric Company, a corporation of
New York

Application November 28, 1949, Serial No. 129,828

1 Claim. (Cl. 339—66)

1
My invention relates to electrical sockets, and, more particularly, to electrical sockets which are adapted for electrical contact-making engagement with the base pins of an electron discharge device. While my invention is of general utility, it is particularly suitable for making electrical contact with the active pins of a cathode ray viewing device.

In certain devices of the electron discharge type, provision is made for a relatively large number of contact pins in the base thereof, whereas only a few contact pins are actually connected to the internal electrodes of the device. Such a situation is found in the cathode ray tube art wherein it is standard practice to utilize a duodecimal type base, having space for 12 contact pins, although only a small group of 5 adjacent pins need be energized for proper operation of the device. To establish electrical contact with the cathode ray tube, it is customary to utilize a duodecimal type socket having provision for all 12 pins of a duodecimal type cathode ray tube. Such a socket is expensive, especially if it is to be used in competitively marketed television receivers, and is complicated and difficult to assemble. Accordingly, it is a primary object of my invention to provide a new and improved electrical socket which is particularly adapted for use with a cathode ray tube having a duodecimal type base.

It is another object of my invention to provide a new and improved electrical socket which is adapted for use with a duodecimal base cathode ray tube and which is relatively inexpensive.

It is a further object of my invention to provide a new and improved electrical socket for a duodecimal base cathode ray tube which is simple in construction and may be readily assembled in production.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 is a front elevational view of one form of my improved cathode ray tube socket mounted on a cathode ray tube, Fig. 2 is a fragmentary side elevational view of the assembly of Fig. 1 with the tube socket shown in vertical cross-section along the reference line 2—2 of Fig. 1 and Figs. 3 and 4 are similar front and side elevational view respectively of an alternative embodiment of my invention.

2
Referring now to Fig. 1 of the drawing, my improved cathode ray tube socket which is indicated generally at 1, is therein illustrated as mounted in operative position upon the base portion 2 of a cathode ray tube of the duodecimal base type. In the drawing, the cathode ray tube is viewed from the base end thereof and it will be understood that the cathode ray tube is supported by means not shown in the drawing so that its neck and base portion extends horizontally. Such an arrangement is customary in conventional direct-view television receivers, wherein in the screen of the cathode ray tube is disposed in a substantially vertical plane. The base of the cathode ray tube is provided with a central locating pin 3 which is provided with a longitudinally extending key portion 4.

In the duodecimal base 2 provision is made for a plurality of contact pins which are equiangularly spaced about the central locating pin 3 and which extend through bosses 6 formed in the base member 2. However, in present day cathode ray tubes, which utilize electromagnetic scanning coils which are exterior to the cathode ray tube, only five contact pins 5a-5e adjacent the key portion 4 are utilized for electrical connection to the interior electrodes of the cathode ray tube. The remainder of the contact pin positions remain unused and in most instances these pins are not brought out through the base. In all cases, those ones of the bosses 6 which are adjacent each end of the active group of contact pins 5a-5e, that is, the bosses 7, are conventionally left blank, as shown, and no contact pins are present in this area.

In order to provide an electrical socket which will establish electrical contact with the active pins of the base 2 and yet will be relatively inexpensive and simple in construction, my improved socket is provided with an annular segmental base portion 10 which is of somewhat greater radial width than the corresponding dimension of the base 2. The base portion 10 is provided with fine spaced electrical receptacles 11a-11e which are positioned so as to make electrical contact with the corresponding active pins of the cathode ray tube base.

In order to prevent misalignment of the base portion relative to the active contact pins of the cathode ray tube, there is provided in the base 10 a key way portion 12, the key way 12 being so positioned along the inner surface 13 of the annular segmental base portion 10 as to register with the key 4 of the cathode ray tube base. Thus, proper registering between electrical receptacles 11a-11e and the corresponding active

contact pins 5a-5e is assured by proper registering of the key way 12 with the key 4.

In order further to prevent misalignment of the cathode ray socket with the base of the cathode ray tube base, the base portion 10 is provided with end portions 15 which overhang the area which would be occupied by the next adjacent contact pin. By such an arrangement, the electrical receptacles cannot be engaged with any of the contact pins unless there are no contact pins immediately beneath the overhanging end portions 15. Such a situation obtains only when the base portion is properly registered with respect to the active contact pins of the cathode ray tube base. Otherwise, as will be apparent from inspection of Fig. 1, there would be three angular positions of socket 1 relative to tube base 2 in which the key 4 would be out of engagement with the inner periphery of base portion 10 and in which it would be possible to make improper engagement of one or more of the contact pins and receptacles. Specifically, without the overhanging end portions 15 it would be possible to make improper engagement of pin 5a with receptacle 11e, or of pins 5d and 5e with receptacles 11a and 11b, or of pin 5e with receptacle 11a. However, by employing both the keying arrangement and the overhanging end portions 15, the socket 1 may only be mounted on the cathode ray tube base when they have the relative angular positions shown in the drawing.

In Fig. 2 there is illustrated a side elevational view of my improved cathode ray tube socket mounted in position on the base portion 2 of the cathode ray tube, the socket being shown in vertical cross-section along the line 2-2 of Fig. 1. This figure illustrates more clearly the relative positioning of the contact pin 5c, the key portion 4 of the cathode ray tube base and the electrical receptacle 11c therefor. It is evident from an inspection of Fig. 2, that the key portion 4 extends outwardly from the end of base 2 further than the contact pins (i. e., further to the left as viewed in Fig. 2). Therefore, when the socket is pressed into engagement with base 2, the key way 12 of the base portion 10 must necessarily engage the key 4 before contact is made between receptacles and contact pins.

Fig. 2 also illustrates more clearly the construction of electrical receptacles 11 which are provided with a terminal portion 14 having a wire receiving opening 18 therein. The pin engaging portions of the receptacles 11 and the terminal portion 14 thereof are joined through an intermediate portion 16 which is positioned on the opposite side of the base 10 and extends through apertures 17 to meet the terminal 14. By such an arrangement, the receptacles are supported entirely by the single base plate 10, the terminals 14 extending radially from the center thereof.

To provide further protection against the misconnection of contact pins and receptacles and to the end that the conductors connected to the electrical socket may be readily cabled together, the alternative embodiment illustrated in Figs. 3 and 4 may be employed. Certain portions of the structure of Figs. 3 and 4 are identical to those of Figs. 1 and 2 and hence have been identified by identical reference numerals. Therefore, further discussion thereof need not be made herein. In the alternative embodiment of Fig. 3, I provide a second annular segmental base member 20 which is similar in shape to the base member 10 and which is connected thereto by

means of rivets 21 which are positioned in the outer corners of the base members. The base plate 20 is provided to prevent accidental electrical contact between the contact pins 5 and the intermediate portions 16 of the electrical receptacles positioned between the base plates 10 and 20. To this end, the base plate 10 is provided with equiangularly spaced apertures 22 which are of suitable size to admit the contact pin 5 but which do not expose the remaining portion of the electrical receptacle.

The terminal portions 14 of the electrical receptacles of Fig. 3 are arranged to extend rearwardly of the socket base members so that conductors which are to be connected to the five active pins of the cathode ray tube may be cabled together as a single unit and may be readily connected to the terminal portions 14 of my cathode ray tube socket. Thus, the conductor portion 25 of a conductor 26 may be positioned within the aperture 18 in the end of the terminal and secured thereto by means of soldering or the like. As is more clearly illustrated in Fig. 3, the conductors which are connected to the terminal portions 14 of the electrical receptacles 11 may readily be grouped to form a single cable unit which may extend from the base portion of the cathode ray tube to the electrical chassis of the television receiver.

From the foregoing it is seen that the invention makes it possible to provide an electrical socket for a duodecimal based cathode ray tube which requires only the relatively small group of active contact pins for the support and registering thereof with the base portion of the cathode ray tube. With this arrangement, the electrical socket for the cathode ray tube is of extremely low cost and requires relatively simple assembly in mass produced equipments, such as television receivers and the like. The particular construction described insures that proper alignment between the active pins of the cathode ray tube base and the electrical receptacles positioned on the annular segmental electrical socket is obtained before electrical contact is made.

While the invention has been described by reference to particular embodiments thereof, it will be understood that numerous modifications may be made by those skilled in the art without departing from the invention. I therefore aim in the appended claims to cover all such equivalent variations as come within the true spirit and scope of my invention.

What I claim as new and desire to secure by Letters Patent of the United States is:

A sectoral tube socket for use with a cathode ray tube, or the like, of the type having provision for a plurality of equiangularly spaced contact pins positioned on an arc of less than 180° around a central keyed locating pin, comprising an annular segmented base portion of insulating material, the inner peripheral surface of said base portion provided with a reentrant keyway and shaped to conform to the contour of a part of said central keyed locating pin in only one position, said reentrant keyway acting as barrier means to facilitate alignment of said base portion with said tube base in said one position, and a plurality of equiangularly spaced electrical receptacles mounted and positioned on said base portion to engage said contact pins in said one position, said base portion having end portions extending circumferentially beyond each outermost electrical receptacle an arcuate distance at least equal to the arcu-

ate distance between the centers of any two adjacent electrical receptacles, the radial edges of said extending end portions acting as barriers to prevent improper engagement of any of said contact pins with said electrical receptacles thereby permitting said electrical receptacles to engage said contact pins in only said one position.

DONALD B. KEIM.
